C. GIRL

AUTOMOBILE BUMPER

Filed March 17, 1924.

Inventor
Christian Girl,
By Hull, Brock & Max
Atty's

UNITED STATES PATENT OFFICE.

CHRISTIAN GIRL, OF DETROIT, MICHIGAN.

DESIGN FOR AN AUTOMOBILE BUMPER.

Application filed March 17, 1924. Serial No. 8,962. Term of patent 14 years.

To all whom it may concern:

Be it known that I, CHRISTIAN GIRL, a citizen of the United States, residing at Detroit, in the county of Wayne and State of Michigan, have invented a new, original, and ornamental Design for Automobile Bumpers, of which the following is a specification, reference being had to the accompanying drawing, forming part thereof, wherein—

Fig. 1 represents a plan view and Fig. 2 an elevation of a bumper exhibiting my new design.

I claim:

The ornamental design for an automobile bumper, as shown.
